DESIGN FOR A SOAP DISH

David Bernikow, Brooklyn, N. Y.

Application April 16, 1940, Serial No. 91,711

Term of patent 7 years

To all whom it may concern:

Be it known that I, David Bernikow, a citizen of the United States and a resident of the city of New York (Borough of Brooklyn), county of Kings, and State of New York, have invented a new, original, and ornamental Design for a Soap Dish, of which the following is a specification, reference being had to the accompanying drawing, forming part thereof, in which—

I claim:

The ornamental design for a soap dish, substantially as shown.

DAVID BERNIKOW.
